UNITED STATES PATENT OFFICE.

WALLACE L. BROOKS, OF SCHENECTADY, NEW YORK, ASSIGNOR TO GENERAL ELECTRIC COMPANY, A CORPORATION OF NEW YORK.

CONSTRUCTION OF CURRENT-CARRYING RESISTORS.

1,413,001.

Specification of Letters Patent. Patented Apr. 18, 1922.

Application filed November 2, 1920. Serial No. 421,367.

To all whom it may concern:

Be it known that I, WALLACE L. BROOKS, a citizen of the United States, residing at Schenectady, county of Schenectady, State 5 of New York, have invented certain new and useful Improvements in the Construction of Current-Carrying Resistors, of which the following is a specification.

My invention relates to the construction 10 of current-carrying resistors and more particularly to such resistors formed of metal strips between terminal bars, used in electrical measurements.

It is quite customary to use as a resistance element the alloy manganin, especially 15 for accurate measurements where it is essential that errors due to varying temperature be minimized. To provide terminals for these strips of manganin, copper terminal bars are utilized which also serve to 20 carry the appropriate binding screws to connect the manganin strips to an outside circuit. It has been found that difficulties occur when it is attempted to solder the 25 manganin strips directly to heavy copper terminal bars. This difficulty arises from the fact that it is necessary to use silver solder to make a good connection which will not be affected by conditions of service. 30 A high temperature must be used to perform this soldering operation. Since the terminal bars have a relatively large mass, it is difficult to keep them heated at the required temperature without heating the 35 alloy to a point which destroys its electrical and mechanical characteristics. Especially is this true where a plurality of strips are joined to a common terminal bar. It is thus the main object of my invention to facilitate 40 the securing of the manganin strips to the terminal bars.

For a better understanding of my invention, attention is called to the accompanying drawing in which Fig. 1 is a view in 45 perspective, showing the entire current-carrying resistor constructed according to my invention; and Fig. 2 is a detail view showing on an enlarged scale how the manganin strips are held to the terminal bars. 50 Referring now more in detail to the drawings, in which like reference characters refer to like parts throughout, the resistance element 11 is formed of a thin strip of manganin bent back and forth upon itself 55 in the manner clearly shown and appropri-

ately held on an insulating base 12 by means of the insulating blocks 13. The ends of the strip 11 are secured in the holders or terminal bars 14 which carry the binding screws 15 for appropriate connection of 60 the resistor into the circuit. The character of the metals made use of is such that to solder them together with ordinary solder they would have a variable resistance value in service; to remedy this, silver solder and 65 a relatively high temperature must be used. Since the mass of the copper terminal bars 14 is quite large, a difficulty presents itself in doing this without overheating and disturbing the electrical characteristics of the 70 manganin. To overcome this difficulty I make use of a member 16 of relatively small mass which is ordinarily made of copper and which embraces the strip 11 as shown in Fig. 2. This copper element 16 is first 75 soldered with silver solder to the manganin strip 11 and since its mass is small, no difficulty is experienced in effecting a proper union, and in retaining the alloy in its proper condition. After this is accomplished, the member 16 is appropriately 80 soldered with ordinary solder within the terminal bar 14 in which a slot may be milled within which the member 16 may be inserted. The layers of solder connecting 85 the elements are indicated at 17.

While I have shown one embodiment of my invention, I do not wish to be limited thereto but aim to embrace in the appended claims all modifications falling fairly within the scope of my invention.

What I claim as new and desire to secure by Letters Patent of the United States, is:

1. In a current-carrying resistor, in combination, a manganin strip, copper terminal bars for said strip, copper members each embracing said strip and soldered to the strip and to the terminal bars.

2. In a current-carrying resistor, in combination, a pair of copper terminal bars, 100 each of said bars having a slot, a manganin resistance strip, and a pair of U-shaped copper elements each embracing an end of said strip and soldered thereto, said elements being also soldered within the slots in the 105 terminal bars.

In witness whereof, I have hereunto set my hand this first day of November, 1920.

WALLACE L. BROOKS.
